United States Patent Office.

ELIAS A. PAIN, OF SUTTON, MASSACHUSETTS.

Letters Patent No. 78,229, dated May 26, 1868.

IMPROVEMENT IN SHUTTLES.

The Schedule referred to in these Letters Patent and making part of the same.

KNOW ALL MEN BY THESE PRESENTS:

That I, ELIAS A. PAIN, of Sutton, in the county of Worcester, and Commonwealth of Massachusetts, have invented certain new and useful Improvements in Shuttles; and I do hereby declare that the following is a full, clear, and exact description of the same, reference being had to the accompanying drawings, forming a part of this specification, which represents a longitudinal central section of a shuttle having my improvements applied thereto.

To enable those skilled in the art to which my invention belongs to make and use the same, I will proceed to describe it more in detail.

In the drawings, the body of the shuttle is lettered A, and the spindle B, the spindle B being hinged or pivoted to the body of the shuttle, as shown at a. The lower part of the head C of the spindle, from 1 to 2, is made concentric with the pivot a, while the front part of the head is cut away, as shown at 3.

The catch D, which holds the bobbin E, is fastened at its rear end to the lever b, which in turn is pivoted at c to the body of the shuttle. The rear end of lever b is forced out by a spiral spring, d, placed in a circular hole cut in the shuttle-wood, as indicated in the drawings. The front part of lever b is made in cam-form, as shown at 4 in the drawings.

The front hooked end e of the catch D enters the notch f of the bobbin, thereby holding the latter securely in place upon the spindle, while the shuttle is in use in the loom.

The operation is as follows: The operative, after the yarn has been woven from the bobbin, raises the spindle, as shown in red lines in the drawings, removes the empty bobbin, and puts on a full one, when the spindle is turned back into the shuttle, the hooked end e of the catch D catching into the notch f of the bobbin, where it is held by the pressure of spring d upon the rear end of lever b, to which the rear of the catch is fastened by a rivet, g.

It will be observed that when spindle B is first raised, the point 1 of head C will strike against cam 4 of lever b, thereby forcing out the front end of lever b, together with the hooked end e of the catch D from the notch f in the bobbin-head.

It will also be observed that after point 1 of head C has passed the cam 4, and released the catch from the bobbin-head, as before explained, but little, if any, outward motion is imparted to the front end of lever b and catch D by the subsequent and further elevation of the spindle, since the head C, from the point 1 to 2, is made upon a circle, or nearly so, the centre of which is the axis of motion of the spindle.

By the above mode of combining the holding-device of the spindle and bobbin, a quick motion is obtained for releasing the catch from the bobbin-head, while the subsequent outward motion of the spindle occasions but little wear or friction of the parts, since the cam 4, during the latter part of the said operation, presses upon the circular part from 1 to 2 of head C.

As cam 4 is arranged to press upon the part 1 of head C, which is back of the centre of motion of the spindle, the latter is held, by the action of the spiral spring, in the proper position to support the bobbin during the operation of weaving.

The slot in the shuttle-wood is so cut that the wood is struck by the back part h of the head C of the spindle when the latter is in the position shown in dark lines in the drawings.

Again, by the combination of the "catch" with the lever b, as shown, the front end of lever b will always be forced in against the point 1 of the head C, even though the point e of the catch is arrested by the bobbin-head, since there is considerable elasticity or spring to the catch, which can be made quite thin, as its only function is to hold the bobbin in place.

All the parts for holding both the spindle and bobbin are arranged upon one side of the shuttle, and in a compact form, no part being liable to get out of order or become displaced—features which will commend themselves to all practical manufacturers.

In case the shuttle is to be used for weaving with cops, a cop-spindle being used, the catch may be left off,

all that is necessary in such cases being to hold the spindle properly in place, which can be effected by the lever *b*, applied as shown in the drawings.

Having described my improved shuttle, what I claim therein as new and of my invention, and desire to secure by Letters Patent, is—

The combination with the spindle-head, formed between the points 1 and 2 and the points 1 and 3, in the manner specified, of the lever *b* and its cam 4, and the spring for actuating said lever, with or without the bobbin-holding catch, the said parts being constructed and arranged for operation as herein shown and set forth.

ELIAS A. PAIN.
